UNITED STATES PATENT OFFICE.

JOHN A. JESSEN, OF WINTHROP, MASSACHUSETTS, ASSIGNOR TO THE PALMER ELECTRIC & MANUFACTURING COMPANY, OF BOSTON, MASSACHUSETTS, A CORPORATION OF MAINE.

SERVICE SWITCH.

1,417,920.

Specification of Letters Patent. Patented May 30, 1922.

Application filed November 6, 1917. Serial No. 200,591.

To all whom it may concern:

Be it known that I, JOHN A. JESSEN, a citizen of the United States, residing at Winthrop, in the county of Suffolk and State of Massachusetts, have invented new and useful Improvements in Service Switches, of which the following is a specification.

This invention relates to service switches of the general character of that set forth in my previous Letters Patent No. 1,209,445, dated December 19, 1916, and has for its object to provide certain improvements therein which are hereinafter described.

According to my present invention, the switch is enclosed in a metal case and is designed for manual operation without opening the case, the construction and arrangement of parts being such that, when the case is opened, the terminals are dead, thereby eliminating the possibility of shock to an operator in inspecting or replacing fuses. The movable switch members, between each pair of which is a removable fuse, are located upon a slide which is operated by toggle mechanism. This toggle mechanism is primarily actuated by an oscillatable member arranged to be moved manually, the parts being so constructed and arranged that, when the toggle mechanism occupies approximately dead-center positions, it holds the slide and the movable switch members thereon in opened or closed positions as the case may be. Access to the fuses when the switch members are opened is through an opening in the front of the case and a sliding door is therefore associated with the opening and is so related to the oscillatable member by means of interlocking mechanism that said member cannot be moved to close the switch while the door is open, and the door cannot be opened while the switch is closed.

There are parallel barriers so arranged in reference to the door-closed opening and the stationary contact members that, when the door is open, they wholly cut off access to the live or current-carrying parts in the case. These barriers divide the chamber in the case into a central portion in which the fuses are located and where they are accessible through the opening in the front wall or cover of the case, and side portions in which are located the live or current-carrying parts, but which are inaccessible

through said opening by reason of the inter- 55 position of the barriers.

On the accompanying drawings,—

Figure 1 represents in front elevation a service switch embodying the invention, the front wall of the case being moved to expose 60 the interior mechanism. In this figure, the switch is shown as open.

Figure 2 shows the position of the toggle mechanism when the switch is closed.

Figure 3 represents a section on the line 65 3—3 of Figure 1.

Figure 4 represents a section on the line 4—4 of Figure 1.

Figure 5 illustrates the case in front elevation with the door closed. 70

Figure 6 illustrates the slide and its actuating mechanism together with the associated parts, all of which are bodily removable as a unit from the case.

Figure 7 illustrates the position of the 75 handle when the switch is closed and shows in dotted lines the parts for holding the door against movement at this time.

Figure 8 illustrates the bottom of the case and shows how the cover is locked in place. 80

In the various figures, the parts are shown as though the switch were laid upon a table and not affixed to a vertical wall. In the description, however, the parts will be referred to as though the case were affixed to 85 a vertical wall, and it is with this understanding that the terms front, rear, top, bottom and the like are employed.

The switch is located within a case which is preferably of metal and which may be of 90 any suitable shape or design. As illustrated, the case is rectangular and it consists of sheet metal shaped and bent to provide a rear wall 10, top and bottom walls 11, 12, and side walls 13, 14. The 95 top, bottom and side walls may be provided with the usual knockout plugs which may be removed to permit electrical conductors to be passed into the case from any direction, but such construction is so common 100 that I have not illustrated the removable plugs. The cover of the case is illustrated at 15 and it has marginal flanges 16 which overlap the top, bottom and side walls of the case. Any suitable means for securing 105 the cover in position may be utilized. For example, I have illustrated the top wall 11 as being provided with pins or projections

17, 17, to extend through complementary apertures in the top flange of the cover, as shown in Figure 3. The bottom wall 12 of the case is provided with a lug 18 to 5 extend through a slot in the front of the cover near its lower edge. The lug 18 has an aperture 19 to receive a seal or padlock or other locking device 20. The details of construction of the case and its cover are 10 not essential or material, it being only necessary to provide a sufficiently strong closed metal case so as to meet the requirements of the National Board of Fire Underwriters. The cover, as shown in 15 Figure 5, is provided with an opening 21 which is shown as rectangular and which is adequate in dimensions to permit access to the fuses. Associated with this opening is a sliding door 22. The door is arranged 20 to slide in guideways 23, 24, and its movement in opposite directions is limited by a projecting knob 25 which occupies semi-circular recesses 125, in the side walls of the opening when the door is at one or the 25 other extremity of its movement. The interlocking mechanism, by which the switch is locked in an open position when the door is open and the door is locked in a closed position when the switch is closed, will be 30 subsequently described.

The switch mechanism will now be explained. As illustrated, it consists of a base plate 26 which is secured by suitable fastenings to the back wall 10 of the case, 35 so that it, together with the parts that are mounted thereon, may be removed bodily from the case on removing the fastenings which hold said plate in place. Upon the plate are secured two parallel strips or bars 40 27, 28, of slate, fiber or other insulating material upon which the respective pairs of stationary contact members are mounted or secured. Any suitable number of pairs of stationary members may be used, although 45 I have illustrated three pairs, the two members of each pair being indicated at 29 and 30. These stationary contacts are of the spring clip variety to receive a knife member between the spring jaws thereof. Upon 50 the plate 26 there is located a sliding plate 31 which has flanges 32, 33, at its ends. These flanges are apertured to receive parallel guide bars 34, 35, the lower ends of which are set in an up-turned flange 36, 55 at the end of the plate 26. Upon the sliding plate 31 there is affixed a block 38 of insulating material, see Figures 3 and 4, upon which are secured the movable switch members or terminals in pairs equal in number to the pairs of stationary switch members. The members of each movable pair are indicated at 39 and 40, and they are 60 of the knife type so as to enter the spring jaws of the stationary members. Each of 65 the movable members is provided with

spring clips 41 to receive a fuse of which one is illustrated in Figure 1 at 42. Of course any suitable fuses may be employed and the movable switch members will be adapted to receive the same so as to permit 70 their removal and replacement when desired. In Figure 1, the slide, comprising the plate 31 and the block 38, is in its inactive or open position with the movable switch members disengaged and remote 75 from the stationary members. The slide is moved by a toggle which comprises the two members 43, 44. The member 43 consists of a bifurcated arm projecting radially from the shaft 45 and it is pivoted by a 80 screw pin 146 to the member 44 which is pivoted by a screw pin 147 to the sliding plate 31, as best shown in Figure 6. The member 44 is curved, as shown, to permit the oscillatory member or rock shaft 45 85 to be swung through an arc a little greater than 180° from the position shown in Figure 1 to the position shown in Figure 2. In these two figures, it will be seen that the two members occupy approximately dead-center positions so that the slide is locked by the toggle mechanism in its open or closed positions as the case may be. To limit the opening movement, the member 44 has a lug or stop 46 adapted to engage the side 90 edge of the member 43. I employ helical compression springs 47 strung upon the guide bars 34, 35, to assist in opening the slide and the switch when the toggle members have been moved from their dead-center position by a partial rotation of the 95 shaft 45. The shaft 45 projects through the cover, as shown in Figure 3, and upon its projecting end there is a handle consisting of a crank arm 48 and a knob 49. 100 By means of this crank handle, the shaft may be oscillated in one direction or the other. When the switch is opened, the handle occupies the position illustrated in Figure 1, and to close the switch the handle 105 must be swung clockwise through an arc of slightly greater than 180° until the toggle members are in the position shown in Figure 2. If desired, the crank handle may be locked in the position shown in Figure 1, 110 and to this end the arm 48 is provided with a lateral projection or lug 50 having at its end a flange 51 closely adjacent the lug 18. The flange 51 is provided with an aperture 52 close to an aperture 53 in said lug so that the seal or padlock 20 may have its hasp passed through said apertures 115 so as to lock the handle to the lug 18. In this case, the single seal or padlock securely locks together the body of the case, the cover 120 and the switch-operating handle. Ordinarily, however, the seal or padlock will be engaged only with the lug 18 as shown in Figures 7 and 8, so that the switch handle 125 may be operated.

From the foregoing description, it is now apparent that, by means of the oscillatory member 45, its actuating handle and the toggle, the slide carrying the movable switch 5 members may be moved to opened and closed positions as desired.

In order that access to the live or stationary terminals may be cut off, the slide is provided with two parallel upright strips 152 of insulating material, see Figure 4. The lower portions of these strips, which constitute barriers or division walls, are secured to the block 38, and they project towards the cover of the box, so that their outer edges are 10 so close thereto that a wire or an instrument cannot be passed between the cover and the said barriers. The barriers occupy positions between the side edges of the block 38 and the pairs of stationary contacts, as shown in 15 Figures 1 and 4. The flat knife members of the movable switch element project through apertures in the barriers 152. The relation of the opening 21 in the cover to the movable slide is such that, when the slide occupies the 20 position shown in Figure 1, it is immediately in the rear of the opening so that the fuses are exposed and may be easily inspected or replaced, and, when the slide is in this position, the door is capable of being 25 opened to permit such inspection and replacement. Interlocking mechanism, however, is provided, to prevent the door from being opened except when the switch is in its open position, and to prevent the switch 30 from being closed while the door is opened. This interlocking mechanism consists of two simple elements, one of which is located upon the door itself and the other of which is formed on or connected to the oscillatory 35 shaft or member 45. It may be remarked incidentally that the shaft 45 is journaled at one end in the plate 26 and at its other end in an arm 60 projecting laterally from an upright 61 attached to the flange 36 of the 40 plate 26. The door is provided with a lateral extension, illustrated in dotted lines in Figure 5 and indicated at 62. The door extends below the opening 21 and its lower laterally-extended portion is provided with a 45 forwardly extending flange 63, see Figures 3 and 4. This flange constitutes one element of the interlocking mechanism. The other element consists of a disk 64 formed on or secured to the shaft 45. The disk is closely 50 adjacent the flange, as shown in Figures 3 and 4, and is formed with a plane face on its periphery, which, when the switch is opened and the parts occupy the relative positions shown in Figure 1, is parallel with the flange 55 63. The flange 63, however, is interrupted so as to provide a recess 66, see Figure 4, of adequate length to permit the curvilinear portion of the disk to move thereinto when the recess registers with the disk as shown in 60 Figure 4. When the disk moves into the re-

cess, of course it locks the door against lateral movement. When the switch is opened, as illustrated in Figure 3, so that the handle 48 and the disk 64 are in the position shown in Figure 1, the plane face of the disk is parallel with the flange 63 of the door and the door may then be moved to the right, see Figure 5, to expose the opening in the cover. When the door is moved to any extent to the right, a portion of the flange 63 slides across 70 the plane face 65 of the disk and prevents the rotation of the disk. Consequently the oscillatory member or shaft is locked against movement to prevent the closing of the switch when the door is opened. When the door is moved to the left to close the opening in the cover, the recess registers with the disk 64 so that the handle 48 may then be 75 oscillated to return the switch to its closed position. The curvilinear portion of the 80 disk during this operation moves into the recess 66 in the flange and lies in the path thereof so as to prevent the door from being opened at all times when the switch is closed or partially closed. The switch is actually 85 held locked in its closed position when the door is closed for the reason that the members of the toggle occupy a substantially 90 dead-center position, as illustrated in Figure 2, but this does not prevent the operation of 95 the toggle by the manual actuation of the operating handle to open the switch. On the other hand, when the switch is in open 100 position as in Figure 1, it is held locked in that position by the toggle members which 105 are in practically dead-center position, and the toggle members themselves are locked against movement by the engagement of the face of the flange 63 with the plane face of the disk.

Assuming that the switch is closed, and that the door is closed and locked, the switch handle 48 will occupy the position shown in Figure 7. At this time the disk 64 has entered the recess in the flange 63 and holds 110 the door against opening movement. Should an inspector desire to examine the fuses, it is necessary for him to perform the following operation. He first swings the handle anti-clockwise from the position shown in Figure 7 to the position shown in Figure 5. This has the effect of partially rotating the disk so that the flat face thereof is parallel 115 with the flange 63 of the door, and also has the effect of moving the switch to the open position as illustrated in Figure 1. The door may now be opened by moving it to the right in Figure 7. As soon as the door has been moved partially to the right, the flange 63 slides across the flat face of the disk 120 and holds the latter against rotation so that the switch is securely locked in open position with its terminals or movable switch members dead. When the door is opened, 125 the live terminals or stationary contacts 29 130

and 30 are impossible of access because of the barriers 152 which lie between the side walls of the opening in the cover and such terminals. With the door open, the inspector may now examine the fuses and replace them. In order that the switch may be closed, it is first necessary to move the door from its right-hand position to the left-hand position shown in Figure 5, so as to bring the recess 66 into registration with the disk, whereupon the operating handle 48 may be swung clockwise from the position shown in Figure 5 to the position shown in Figure 7. When the door occupies the position shown in Figure 7, anyone, if he so desires, may open the switch. If the inspector desires to prevent a customer from using the circuit, he may, after opening the switch, lock or seal the handle 48 in its open position by engaging the seal or lock with the member 50 and the lug 18.

In the construction which is herein illustrated, the slide, with the terminals thereon, constitutes a movable switch member, and also a fuse carrier.

Of course it will be understood that the invention is not limited to the exact details of construction which I have illustrated and herein described, and that various changes may be made in the structure without departing from the spirit and scope of the invention as defined in the claims.

Having thus explained the nature of my said invention and described a way of making and using the same, although without attempting to set forth all of the forms in which it may be made or all of the modes of its use, what I claim is:

1. A closed metallic case having a slidable door, stationary line contacts in the case, a carrier in the case having movable contacts for engaging and disengaging the line contacts, a rock shaft, operative connections between said shaft and said carrier, a cam on said shaft, and an associated member on said door, whereby the door is locked shut when the carrier is in closed position, and the carrier is locked in open position when the door is open.

2. A closed metallic case having a slidable door, stationary line contacts in the case, a carrier in the case having movable contacts for engaging and disengaging the line contacts, a rock shaft, a toggle connecting said shaft and said carrier and arranged to automatically lock the carrier in open and closed positions respectively, a cam on said rock shaft, and an associated member on the door by which the carrier is locked in open position when the door is open.

3. A closed case having an opening, a slid- able door associated with said opening, a movable switch member, an oscillatory shaft supported in the case independently of the door for actuating said member, power-

transmitting means between said shaft and said switch member for moving the latter to open and closed positions, and interlocking devices on said door and said shaft respectively whereby one may prevent the operation of the other.

4. A closed case having an opening, a slidable door associated with said opening, a movable switch member, an oscillatory shaft supported independently of the door for actuating said member, power-transmitting means between said shaft and said switch member to move the latter to open and closed positions, and interlocking mechanism comprising a flange on the door and a cam on and rotatable with said shaft.

5. A case, parallel guides supported by one of the walls of the case, a slidable fuse carrier guided by said guides, an oscillatory shaft supported within the case, a crank handle connected to said shaft and projecting through the front wall of the case, a toggle connecting said shaft and said fuse carrier and arranged when in dead center positions to lock said carrier at its extremes of movement, an operating rock shaft connected to said toggle, and interlocking members on said shaft and said door.

6. A case, and mechanism removable as a unit therefrom and comprising a removable base plate, a slidable fuse carrier thereon, fuses and terminals or movable contacts on the carrier, stationary contacts supported by said plate, and a rock shaft supported by said plate and connected to the fuse carrier to actuate it.

7. A closed case having an opening, a door normally closing said opening, a slid- able fuse carrier in the case, a rock shaft, operative connections between said shaft and said carrier, a cam on said shaft having a flat peripheral face, a flange on said door adjacent said cam and having a recess to receive the curvilinear periphery of said cam when the door is closed and the fuse carrier is in active position.

8. A case provided with an opening in its front wall, and a door associated with the opening, stationary contacts located within the case, a movable slide in the case accessible through the door opening and carrying fuse terminals for engagement with and disengagement from said stationary contacts, parallel barriers located between the stationary contacts and the door by which access to said stationary contacts is prevented when the door is opened, a rock shaft journaled in the case and projecting through the front wall thereof, slide-operating devices actuated by said shaft, a cam on said shaft, and a flange on said door, whereby the door is locked when the slide is in closed position.

9. A switch mechanism comprising a case having a front wall with an opening therein, a door normally closing said opening, a

5 fuse carrier in the case having movable contacts and a fuse which is accessible through said opening but is normally concealed by said door, stationary contacts inaccessible through said opening and adapted to be engaged by the movable contacts, a rock-shaft, a toggle connection between said shaft and said carrier, a rotary locking member on said shaft, and an associated member on

said door, said members preventing the door 10 from being opened when the carrier is in closed position and preventing the carrier from being moved to closed position when the door is open.

In testimony whereof I have affixed my 15 signature.

JOHN A. JESSEN.
